B. Underwood
 Printing Oil Cloths
 No 10483 Patented Jan 31 1854

UNITED STATES PATENT OFFICE.

BENJAMIN UNDERWOOD, OF BROOKLYN, NEW YORK.

CONSTRUCTION OF PRINTING-BLOCKS.

Specification of Letters Patent No. 10,483, dated January 31, 1854.

To all whom it may concern:

Be it known that I, BENJAMIN UNDERWOOD, of the city of Brooklyn, county of Kings, State of New York, have invented 5 a new and improved mode of producing blocks, patterns, devices, or designs with which to print ornamental figures in colors upon oil-cloths, carpets, and other fabrics; and I do hereby declare that the following 10 is a full and exact description thereof.

The nature of my invention consists in providing a series of suitable movable types of wood, metal or other material, and so arranging them together that they shall, collectively, 15 constitute blocks, patterns, designs or devices, with which ornamental figures and designs may be printed upon oil cloths, carpets and other fabrics, in one or more colors, just the same as if the said blocks 20 had been engraved or carved according to the usual mode.

To enable others skilled in the art to make and use my invention I will proceed to describe its construction and operation, reference being had to the accompanying drawings, forming part of this specification.

Similar letters refer to like parts.

Figure 1 is a vertical view of one of my cases, filled with types composed into an 30 ornamental design and constituting a "block," ready for printing. The shaded squares represent the position of the elevated or impression types, on the surface of which the coloring matter is applied, when 35 in the act of printing. Now, by stamping said types upon the fabric it is evident that an impression will be left thereon, corresponding to the device indicated by the elevated types. In the figure the space within 40 the case not occupied by the elevated types is filled with low types or spaces. *a, a, a*, sides of case; *a'*, end piece of case; *b*, furniture piece; *c*, screws for locking up; *d*, screws for fastening on end piece *a'*.

Fig. 2 is a vertical view of a case for holding one kind of my movable types, the end piece *a'* being removed. The case *a, a, a*, is represented as being half full of types composed into one half of a design similar 50 to that indicated in Fig. 1. The bottom of this case is grooved, as seen at *g*, which grooves extend across the entire width of the bottom of the case. The types contained in this case all have angular projections on their lower parts which fit and slide in these grooves. Fig. 3 is a section

of this case, showing the grooves *g*, and also the arrangement of a line of the types, with angular projections on the bottoms. *a*, case; *e*, elevated or impression types; *f*, low types or spaces; *g*, triangular grooves.

Fig. 5 is a sectional view of a facsimile plate of the upper surface of the types shown in Fig. 1 copied by the electrotype or cast in metal or other material.

Figs. 6 and 7 are blank types or spaces having angular projections, *h*, on their lower parts. Figs. 8, 9, and 10 are elevated or impression types having similar angular projections, *h*.

Fig. 11, is a furniture piece used in locking up a form of angular bottomed types. This piece also has an angular projection *l*.

The usual mode of producing the ordinary blocks, patterns or devices for printing ornamental figures upon oil cloths, carpets and other fabrics is either to take a solid block of wood, and divide the upper surface into minute squares, by sawing the block cross-wise, and then with a chisel or gouge cut out such of the little squares as the drawing which the workman has before him to follow requires, or to engrave the required design upon the block by the usual mode of engraving, or to drive small pegs of wood or metal into the top of a suitable block of wood, and produce the desired block or pattern in that manner. All these difficult and expensive modes I entirely obviate by using 80 movable types.

When I wish to produce a block, pattern or device for printing oil cloths or other fabrics, I place the drawing of the required block before me just as a printer places his copy before him, and then I set up the design in one of my cases. Previous to commencing I unscrew the screws *d*, (Fig. 1) and remove the end piece *a'*. When using the angular bottomed types, (Figs. 6, 7, 8, 9 and 10) I employ the grooved case (Figs. 2 and 3). Having observed on my copy the number and position of the elevated types and blank types required in the particular line which I am composing, I select the corresponding types, one by one, and place them so that their angular bottom projections *h*, shall enter the groove *g*, in which said projections are made to fit. Then I slide the type down the groove to its appropriate place. In this manner I fill out a 110 line evenly to the sides of the case (*a*) and, repeating the operation according to copy,

fill up the whole case with types. Some of the elevated types contain one impression surface, and some more than one, as in Figs. 8, 9, 10, where *k* shows the impression surfaces and *l* open spaces. When the case is full of types, composed in a design, I finish by putting in, against the types, a metallic furniture piece (*b*, Fig. 11). This also has an angular projection *h* on the bottom. I now screw on the end piece *a'* firmly, by means of screws *d*, which fasten in the other parts of case *a*. This done I turn the screws *c*, which revolve through nuts contained in the end piece *a'*. As I turn these screws (*c*, Fig. 1) they press against the furniture piece (*b*) and push it up against the types. In this manner the whole form is locked up securely, rendering it impossible for any of the types to drop out. I would here remark that the angular projections *h*, fitting in grooves *g*, are intended to afford further security against the possibility of the types dropping out when the block is turned in an inverted position. When my case is filled with types and locked up, as described, it constitutes a block and is ready for printing, or for duplication by the electrotype, or casting or molding in any suitable material. From any such facsimile plate I can

print just as well as from the original types. A section of such a facsimile plate is seen at Fig. 5. When required for cylindrical printing I bend these plates around suitable cylinders, and thus the blocks, patterns designs or devices, which I first set up with movable types, may be applied to print any kind of suitable fabrics much in the same manner that calico printing is accomplished.

Having thus described my invention I claim—

1. The peculiar construction of the type herein described, so that when combined in a case, such as above specified, any given design may be produced for printing oil cloth, carpets or other fabrics as herein fully set forth.

2. I also claim the formation of blocks for printing oil cloth, carpets or other fabrics, by the combination and arrangement of sections or type such as herein particularly described, by which an endless variety of patterns may be produced from the same sections variously disposed, at a comparatively small cost.

BENJN. UNDERWOOD.
